CRADLE FOR USE WITH A TRANSDUCER FOR DICTATING AND LIKE EQUIPMENT

Lawrence M. Heineman, Chicago, Ill., assignor to Permo-
flux Corporation, Chicago, Ill., a corporation of Illinois

Application February 21, 1955, Serial No. 34,605

Term of patent 7 years

(Cl. D26—14)

Fig. 1

Fig. 2

Fig. 1 is a perspective view of a cradle for use with a transducer for dictating and like equipment embodying my new design; and

Fig. 2 is a perspective view looking in the direction opposite to the side shown in Fig. 1.

I claim:

The ornamental design for a cradle for use with a transducer for dictating and like equipment, substantially as shown.
